UNITED STATES PATENT OFFICE.

MILO M. CLARKE, OF WESTERLY, RHODE ISLAND.

CAR-COUPING.

SPECIFICATION forming part of Letters Patent No. 429,886, dated June 10, 1890.

Application filed March 18, 1890. Serial No. 344,355. (No model.)

To all whom it may concern:

Be it known that I, MILO M. CLARKE, of Westerly, in the county of Washington and State of Rhode Island, have invented a new and useful Improvement in Car-Couplers; and I hereby declare that the following is a full, clear, and exact description of the same, reference being had to the accompanying drawings, forming part of this specification.

10 This invention has reference to an improvement in the draw-head for railroad-cars, by which two cars can be automatically coupled together.

The invention consists in providing a draw-head with a bell-shaped end terminating in a cavity, in which two blocks are placed, each one of which has a semi-spherical cavity, which, when the blocks are united, forms a spherical cavity in which the ball of the connecting-link enters, a funnel-shaped cavity formed in the forward end of the blocks, and a locking-fork, as will be more fully set forth hereinafter.

Figure 1 is a plan view of the lower half of the draw-head. The blocks and locking-fork are shown in section. Fig. 2 is a vertical cross-section of the draw-head through the center. Fig. 3 is an end view of the draw-head, showing a hand-lever for raising the locking-fork.

Similar numbers of reference indicate corresponding parts.

In the drawings, the number 5 indicates one end of a connecting-link used for connecting the draw-heads of two cars together. These connecting-links may consist of a rod, on both ends of which the spherical ball 6 is formed; or they may consist of a link, one or both ends of which are united into a short rod and provided with a ball 6. When the two cars to be secured together are provided with my improved draw-head, the link 5 is provided at each end with the ball 6, and to enable a car provided with my improved draw-head to be coupled with a car having the usual pin-and-loop draw-head a loop draw-head provided with a ball 6 at one end is carried on each car, as is shown in Fig. 3.

For convenience in construction the draw-head is made in two parts secured together, the part 7 being the lower half and the part 8 the upper half. The end of the draw-head

is cupped, having the bell-shaped concavity 9, ending in the cylindrical opening 10, constructed so that in moving two cars together 55 the ball of the link secured to one draw-head will be guided into the central cylindrical opening 10 by the bell-shaped concavity 9.

The blocks 11 are of approximately rectangular form, the two blocks together forming a cube slightly wider horizontally at the rear end. The blocks face each other on the line 12. The centers of the spherical cavity 13, the funnel-shaped cavity 14, the cylindrical opening 10, and the bell-shaped cavity 9 65 are all on the line 12. The blocks 11 are placed into the recess 15, formed in the upper and lower half of the draw-head. This recess 15 is of butterfly shape in its horizontal plan, as is shown in Fig. 1, the inner face of the recess, at right angles to the axial line of the draw-head, being of a width sufficient to receive the widest end of the two blocks 11, the said recess enlarging toward the bell-shaped cavity or forward end of the draw-head, 75 so that the blocks may be opened or spread laterally to receive the ball 6, as is shown in Fig. 1 in broken lines.

The upper half 8 of the draw-head is provided with two vertical slots, through which the two arms 16 of the fork 17 pass to lock the blocks 11 and hold the ball 6 on the link 5. These arms 16 extend the height of the blocks 11 between the blocks and the outer walls of the recess 15. The lever 18 may be 85 pivoted in the bracket 19, connected at one end with the fork 17 and provided at the other end with a handle, so that in separating two cars the fork 17 may be raised without entering between the cars, when the blocks 90 11 will open by drawing on the connecting-link 5 and release the ball 6. The arms 16 of the fork 17 will now rest on the blocks, and will be held in the raised position, ready for connection with another car. 95

The operation of coupling is as follows: A connecting or coupling link, provided with a ball 6 at its projecting end, being secured in the draw-head of one car will, on two cars being brought together, be guided by the bell-shaped cavity or cup 9 into the cylindrical opening 10 and pass into the spherical cavity 13, half of which is formed in the open blocks 11. The momentum forces the ball 6 against

the wall of the spherical opening, the blocks 11 will turn on their outer corners as a pivot and close around the ball 6, and the arms 16 will be released and fall between the blocks and 5 the walls of the recess 15, thus firmly locking the blocks and holding the link against any direct pull or strain. The link is free to adjust itself to variation in height, as well as laterally, the connections being a universal 10 ball-and-socket joint.

Having thus described my invention, I claim as new and desire to secure by Letters Patent—

1. An automatic car-coupler consisting of 15 a connecting-link having a ball at the forward end and a draw-head provided with a flaring opening to guide the ball, two blocks having a spherical opening formed half in each block, and a locking-fork constructed to automatically 20 inclose the ball and lock the same, as described.
2. The combination, with the draw-head, of

a railroad-car provided with a flaring opening to receive the coupling-pin, of the blocks 11, provided with the spherical cavity 13 and 25 the locking-fork 17, and the link 5, provided with the ball 6, constructed to automatically secure the coupling-link and lock the blocks, as described.

3. In a car-coupling, the combination, with 30 the link 5 and ball 6, of the draw-head provided with the bell-shaped cup, the cylindrical opening 10, the recess 15, the blocks 11, having the spherical cavity 13, and the funnel-shaped opening 14, the locking-fork 17, 35 and the lever 18, constructed to release the coupling-link and connect the same with the draw-head automatically, as described.

In witness whereof I have hereunto set my hand.

MILO M. CLARKE.
